UNITED STATES PATENT OFFICE.

EUGENE BANTA, WILLIAM JOHN MERRITT, AND HENRY JOSEPH LIPPE, JR., OF NEW YORK, N. Y.

ADVERTISING-CLOCK.

1,204,732.

Specification of Letters Patent.

Patented Nov. 14, 1916.

Application filed July 8, 1914. Serial No. 849,649.

To all whom it may concern:

Be it known that we, EUGENE BANTA, a citizen of the United States, and resident of the borough of Manhattan, city, county, and State of New York, and WILLIAM J. MERRITT and HENRY J. LIPPE, Jr., citizens of the United States, and residents of the borough of Bronx, county of Bronx, city and State of New York, have invented certain new and useful Improvements in Advertising-Clocks, of which the following is a specification.

The device, the subject of this invention is intended as an electric clock of the self winding type and one that is provided with a marine or hair spring escapement.

In constructing our device we have intended that it shall be simple and complete in its operation and although provided with a spring we arrange that the spring shall be of small capacity and that it shall be rewound each hour to an extent equal to the amount freed or unwound during the hour.

Our clock is provided with the smallest number of movable parts that appears possible, that is we have omitted many of the gear and pinions usually found in clocks driving directly from the spring to a time element and controlling the drive so that the proper spacing or proper speed of the time recording elements may be obtained.

The mechanical construction and details of operation will appear in full as the specification progresses.

The following is what we consider the best means of carrying out this invention.

The accompanying drawings form a part of this specification, in which:

Figure 1 shows in elevation our completed device. Fig. 2 is a side elevation of certain parts of the gear mechanism and is on a larger scale. Fig. 3 is a side elevation.

Similar reference numerals indicate like parts in all the figures where they appear.

In developing this invention we have constructed it to be used with an ordinary car card, such cards as are placed between guides arranged adjacent to the inside of the roof of an ordinary street car. The card portion as indicated at 1, is formed of metal which may be sheet tin of any suitable thickness, the metal has its edge forced upward and flanged as shown at 2, to produce a surface which may be engaged in the

guides secured within the car. By forcing the metal upward we produce a sufficient depth for the accommodation and reception of the parts now to be described.

Projecting from the face of the card or metal sheet and formed integral therewith are a plurality of ways as indicated at 3, 4, 5, 6, 7, 8, 9, and 10. Arranged together in pairs and adapted to receive between them suitable strips of card board upon which advertising matter may be printed or produced. These ways utilize about one half of the surface of a card, and upon the other half of the surface of the card we produce a clock dial as indicated at 11. In our drawings we have shown a glass dial secured in a bezel 12 which may be formed integral with the plate, or metal sheet but we desire it understood that we may print or produce the dial upon the metal leaving the hands which operate upon the dial exposed or covered by an additional glass disk.

The clock proper is constructed with a center arbor 13, to which a minute hand 14 is secured. Upon this we arrange a gear 19 and parallel to this arbor we arrange an arbor 15 which supports a spring 16 and spring casing therefor. A ratchet wheel 17 is also secured upon the shaft 15 and loosely operating upon this shaft is a gear 18 in mesh with the gear 19 which is secured upon the center arbor. A gear 20 is secured to, and is rotated with the gear 18, through the medium of a thimble 20' and this gear 20 is in turn in mesh with a broad faced gear 21, which is arranged upon a thimble 21'. The thimble runs freely upon the center arbor 13 to which the hour hand 22 is secured. The thimble runs freely upon the center arbor 13 to which the hour hand 22 is secured. We have arranged a gear 23 driven by the spring 16 which is in mesh with the gear 21^a, arranged upon the thimble 21', and it will be observed that the ratio of these separate gears is such that the hour hand which is driven directly from the spring shall through the train of gears described impart to the minute hand a proper and well understood speed of rotation.

The escapement which is of an ordinary character provided with a ratchet 24 and balance wheel 25 has a pinion directly in mesh with the gear 18.

Within the clock and adjacent to the works thereof we have arranged an electromagnet 26 provided with an armature 27

pivoted to a suitable support as shown at 28, to the free end of the armature 27 we secure a ratchet lever 29 which engages the spring ratchet 17. The lever 29 is held between suitable guides 30 and is retrieved by means of a spring 31.

The contact making device consists of a wheel 32 provided with a pin 33, this wheel is rotated directly from the minute wheel as shown and in contact with one face of the wheel we arrange a spring contact member 34, and a second spring contact member 35 is adapted to be engaged by the pin 33 as shown.

15 The source of electrical supply consists of a battery having a plurality of cells as indicated at 36, 37 and 38. This battery may be supported upon a cleat 39 formed integral with the metal plate or card and between guides 40 and 41 also formed integral with the plate or card 1. A lead wire from the battery is connected to the electromagnet 26 and a second lead wire engages the spring contact 34. From the spring contact 35 we extend a wire to the opposite end of the electromagnet. We may arrange so that the electromagnet will receive one impulse each hour, the impulse will draw the armature toward the magnet and partially 30 rotate the ratchet 17 although the spring may operate the clock for three or four hours or even more, for accuracy and convenience we prefer that the spring shall be rewound at least once every hour.

35 One of the most important features of our construction rests in the fact that this clock will operate even though arranged upon an angle or out of the perpendicular, this is extremely important in the use of this 40 clock in connection with car cards or similar advertising devices.

Having carefully and fully described our

invention what we claim and desire to secure by Letters Patent is:

1. A clock having a spring arbor, a spring thereon a casing surrounding said spring and a gear upon said casing, a second arbor having a thimble rotatable thereon and supporting a clock hand and a plurality of gears one of which is in mesh with said first mentioned gear, a second thimble upon said spring arbor a plurality of gears secured thereto and rotatable therewith, one of which is in mesh with one of the gears on the first mentioned thimble, and a sixth gear secured to the second said arbor and in mesh with a gear upon the second said thimble and another clock hand upon the arbor of, and adapted to be operated by the said sixth gear. 60

2. A clock having a spring arbor, a spring thereon a casing surrounding said spring and a gear upon said casing a second arbor having a thimble rotatable thereon and supporting a plurality of gears one of which is in mesh with said first mentioned gear, a second thimble upon said spring arbor, a plurality of gears secured thereto and rotatable therewith, one of which is in mesh with one of the gears on the first mentioned 70 thimble, and a sixth gear secured to the second said arbor and in mesh with the larger gear upon the second said thimble, in combination with an escapement operated from this larger gear as herein specified. 75

Signed at New York city, in the county of New York and State of New York this 18th day of June 1914.

EUGENE BANTA.

WILLIAM JOHN MERRITT.
